UNITED STATES PATENT OFFICE.

HARRY C. STEWART, OF HARRISBURG, PENNSYLVANIA.

SEWER-TRAP.

SPECIFICATION forming part of Letters Patent No. 274,149, dated March 20, 1883.

Application filed September 25, 1882. (No model.)

To all whom it may concern:

Be it known that I, HARRY C. STEWART, a citizen of the United States, residing at Harrisburg, in the county of Dauphin and State of Pennsylvania, have invented certain new and useful Improvements in Sewer Traps or Valves; and I do hereby declare the following to be a full, clear, and exact description of the invention, such as will enable others skilled in the art to which it appertains to make and use the same, reference being had to the accompanying drawings, and to letters or figures or reference marked thereon, which form a part of this specification.

15 My invention relates to weighted valves, more especially adapted for use as sewer-valves, and it has for its object to construct the valve in such manner that a water luting or seal may be obtained, besides the close joint of the 20 valve upon its seating, to prevent the escape of sewer-gases.

The invention consists essentially in the construction and combination of the valve and valve-seat plate, and their combination with 25 a grating, substantially as hereinafter fully described, and as specifically pointed out in the claims.

30 Figure 1 is a vertical section of so much of a man-hole as is necessary to illustrate my invention. Fig. 2 is an under side view of the valve and its seat-plate. Figs. 3 and 4 are top plan views of the same.

In the above figures of drawings like letters 35 of reference indicate like parts wherever such may occur.

A indicates the masonry or the brick-work of a man-hole, C, at the corner of a street, in which is formed a recess, a, to permit the valve to open wide, and the weighted arms thereof to 40 assume the consequent vertical or nearly vertical position shown in dotted lines, Fig. 1.

B is the gutter that carries the water to the man-hole, and through it to the sewer, provided with the usual covering-plate and a grating, 45 D, to arrest débris, such as sticks of wood or other solid substances that may choke the valve-opening or impair the functions of the valve. In order that access may be had at any time to the valve, or through the valve to the sewer, 50 I hinge said grate in the man-hole in such a manner as to be adapted to be swung to one side,

as shown in Fig. 1, in which said grate is shown as tilted to one side.

E is the valve-plate, which plate may be made square, polygonal, hexagonal, or of other angular shape; or it may be made cylindrical, and the valve-opening e may also be made of any suitable form. The upper face of the valve-plate may be made flat when the masonry in which it is set is flush or practically flush 55 with the valve-opening. When, however, the plate is removably seated upon a supporting-ledge of the masonry, I prefer to make said face either concave or bowl-shaped, or incline the face from all sides toward the valve-opening e, as shown in Figs. 3 and 4.

The valve F is of such a shape as to correspond with the valve-opening, and in the drawings I have shown a rectangular valve hinged to the valve-plate so as to open downwardly. 70 The seat e' for said valve may be made in any desired or usual manner to obtain a tight joint. As shown in Fig. 1, the seat for the valve is formed by a projecting ledge, e', that surrounds the valve, and in which it is seated. The seating may also be formed by means of a rubber packing, E', secured to the seat-plate E by means of clamping-bars E', between which and the seat-plate the rubber gasket is secured, as 75 shown in Fig. 2. The valve has attached thereto or formed therewith one or more bent lever-arms, F', carrying a weight, W, made adjustable thereon by means of set-screws S, as shown. It is evident that the pressure to trip the valve may be adjusted by means of said weights, 80 and consequently a sufficient volume of wafer may be always maintained upon the valve to form a water luting or seal, whereby a valve-closure and water-luting are simultaneously obtained to prevent the escape of sewer-gases 85 into the street or house or other place where such valve is located. By forming the valve-seat plate bowl-shaped or inclined toward the valve-opening such substances as sand or others not retained by the grating are more 90 readily washed out than if the upper face of the seat-plate were flat.

From the above description and by an inspection of the drawings the operation of the valve will be readily understood by all those 95 conversant with this branch of the arts, and needs therefore no further description.

Although I have described and shown the application of a valve to a man-hole of a street-sewer, it is obvious that said valve may be applied to any other sewer-connection or water-discharge, such as sinks or sewer-traps. It is also obvious that no water can back out of the sewer-connection, since the greater the pressure of the water backing up from the sewer the tighter will the valve be held to its seat.

Having now described my invention, what I claim is—

1. In a sewer or other valve, the combination, with the valve-casing or masonry and a downwardly-opening valve held to its seat by adjustable weights, of a valve-seat plate having an outwardly-flaring valve-port, all con-

structed and arranged for co-operation substantially as and for the purposes specified.

2. In a sewer-valve, the combination, with the valve-casing or masonry and a downwardly-opening valve held to its seat by adjustable weights, of a seat-plate having an outwardly-flaring valve-port and the superposed grating D, all constructed and arranged for co-operation substantially as and for the purposes specified.

In testimony whereof I affix my signature in presence of two witnesses.

H. C. STEWART.
